UNITED STATES PATENT OFFICE.

JOHN C. MILLER, OF COVINGTON, KENTUCKY, ASSIGNOR TO THE MILLER PASTEURIZING MACHINE COMPANY, OF CANTON, OHIO, A CORPORATION OF NEW JERSEY.

BOTTLE-WASHING MECHANISM.

1,316,457.

Specification of Letters Patent. Patented Sept. 16, 1919.

Original application filed May 21, 1906, Serial No. 317,918. Divided and this application filed June 15, 1917. Serial No. 174,914.

To all whom it may concern:

Be it known that I, JOHN C. MILLER, a citizen of the United States, residing at Covington, in the county of Kenton and 5 State of Kentucky, have invented certain new and useful Improvements in and Relating to Bottle-Washing Mechanism, of which the following is a specification.

This invention relates to mechanism for 10 washing or cleaning bottles.

One object of the invention is to provide improved means for washing or scrubbing bottles.

Another object of the invention is to provide 15 an improved brush adapted to thoroughly and efficiently clean the interior of a bottle.

With these and other objects in view, the invention consists of the combination or 20 combinations of elements hereinafter set forth.

This application is a division of my application Ser. No. 317,918, filed May 21, 1906.

25 For the purpose of illustration, I have, in the accompanying drawings, shown and herein described one form of brush embodying my invention.

Figure 1 is a fragmentary top plan view 30 of a machine having brushes embodying my invention.

Fig. 2 is a fragmentary side elevation of the parts shown in Fig. 1.

Fig. 3 is a section on the line 3—3 of 35 Fig. 2.

Figs. 4 and 5 are detail views.

Fig. 6 is a perspective view of one of the brushes.

Fig. 7 is a view of the brush with parts 40 broken away.

In the drawings, A indicates the main frame of the machine only part of which is shown. The frame A preferably comprises side plates 2 which carry the working parts 45 of the machine. C indicates a washing mechanism arranged to wash inverted bottles. The bottles are preferably mounted in racks and lowered and raised relative to the washing mechanism by an arm 69, as set forth in my said original application Ser. 50 No. 317,918. G is the conveying system for advancing bottles or groups of bottles through the machine step by step; and H is

the power transmitting devices on the machine for effecting the desired coöperation 55 of its various parts.

The power transmitting devices H preferably comprise a driving shaft 3, which is adapted to suitable bearings at one side of the machine. The shaft 3 is driven in any 60 suitable manner. The shaft 3 is provided with an incline-tooth gear 5 and a worm 6. The gear 5 serves to rotate the scrubbing brushes with which the machine is provided. At the top of the machine are formed opposite rails on guideways 9 for properly directing through the machine said bottle-carrying racks, which are moved along in succession over the rails 9 by reason of their engagement with projecting studs 10, preferably carried upon opposite intermittently 65 operated endless chains 11, which may form part of the conveying system G.

The main washing mechanism C preferably comprises a water tank, head or chest 18 and 75 a series of washers or scrubbing devices, such as brushes 20 for cleaning the interiors of the bottles, this series of brushes being combined with intervening scrubbing devices such as brushes 20^a for cleansing the 80 exteriors of the bottles.

The present machine is designed for use in connection with a rack carrying twelve bottles arranged in three rows of four each, hence there are twelve main brushes 20 correspondingly disposed, and six intermediate brushes 20^a disposed in two rows of 85 three each, so that each of said intermediate brushes will act upon the exterior portions of four bottles, as will be understood upon 90 reference to Fig. 1.

Each of the brush spindles 19 is secured at its lower end to a tubular sleeve 53, which is split at the upper end and provided with a tapering thread for the reception of a 95 clamping nut 54, whereby it may be secured to the lower end of the spindle 19, each sleeve 53 turning in a bearing in the top plate of the chest 18, and in a bearing in a plate 55 above the same and spaced therefrom.

Between the plate 55 and the chest 18 each sleeve 53 is provided with a spur wheel 56 or 57, the spur wheels 56 corresponding with the brushes 20, meshing with each 105 other, but the spur wheels 57 corresponding

with the brushes 20^a meshing only with certain of the spur wheels 56, since it is manifest that said spur wheels 57 cannot mesh with all of the spur wheels 56 because of 5 the contrary directions in which the latter run.

All of the spur wheels 57, therefore, have the upper portions of their teeth cut away and those of the spur wheels 56, which it is 10 not desired to mesh with the spur wheels 57 have the lower portions of their teeth cut away, as shown in Fig. 5, so that the spur wheels 57 mesh only with those spur wheels 56, which have full teeth.

15 Each of the brushes 20 consists of a spindle 19 that is hollow from end to end thus permitting the cleaning solution to flow therethrough from the chest 18. 19^a indicates the fiber material which is secured to 20 the spindle 19. The fiber material extends spirally around the spindle to form a continuous brush from the free end of the spindle downwardly a distance substantially equal to the length of a bottle to be cleaned. 25 This arrangement insures that every part of the bottle wall will be engaged by the brush material. It also permits the convolutions of the brush material to be spaced from each other and the discharge therebetween of jets or streams of cleaning solution to assist the brushes in washing the walls of the bottles. For this latter purpose, the spindle 19 is formed with a plurality of jet openings, preferably uniformly 35 spaced from each other and extending spirally around the spindle between the convolutions of the fiber material. The fiber material may be secured to the spindle 19 in any desired manner. Preferably the spindle 40 is formed with a spiral groove and the fiber material is held in the groove by a wire or band.

59 indicates a ring of brush material arranged at the free end of each spindle 19. 45 The ring-shaped brush 59 preferably surrounds the opening 60 in the spindle end and flares outwardly in order to engage the bottle bottom and annular recess formed by the union of the bottle sides and bottom. 50 The brushes 20^a may be constructed in a similar manner except that the ring 59 may be omitted, since it would, in the brush 20^a, serve no useful purpose.

The brush-carrying chest 18 has no vertical movement, and as the said head or chest 18 and the scrubbing devices carried thereby are arranged in a horizontal plane below the plane of the remaining washing, rinsing and sterilizing mechanisms of the machine, 55 it is necessary to raise and lower the bottles, in the manner already referred to, in order to permit of the entry of the brushes into them and of the proper action of the brushes thereon. For this reason that portion of each of the rails 9 which is adja-

cent to the brushes is disconnected from the remaining portions of said rails 9, these disconnected portions of the rails being united by transverse bars 9^a, so as to form a frame which can be raised and lowered, and upon 70 which each of the bottle carrying racks comes to rest for a time at a certain point in its travel through the machine.

When a tray has been pushed on to the rising and falling frame the latter with the 75 rack containing the inverted bottles is lowered, so that the vertically projecting brushes 20 enter the bottles and the brushes 21^a rise between the same.

The bottles are rotated by frictional contact with the brushes 20, but at a slower rate of speed than the brushes themselves, each brush 20 acting upon all parts of the interior of its respective bottle and each brush 20^a acting upon the exterior of each bottle, with 80 which it is in contact.

In order to prevent the bottles from being lifted from the rack by the upward push of the brushes thereon, the secondary frame has at each side vertical bars 71, bent inwardly and downwardly at their upper ends, 90 so as to be free from engagement with the side frames of the machine, the inner ends of these bars carrying a plate 72, of wire gauze or other light material, which, by contact with the bottoms of the bottles, serves to retain the same in their proper vertical position.

A brush embodying my invention has many advantages, among which may be mentioned the following: (a) It is efficient in operation since the brush material is rotated in a direction substantially in line with the plane in which the material is disposed; accordingly, the material resists flexing in 100 that direction and this resistance causes the brush to operate effectively on the walls of the bottle; (b) the brush being continuous throughout its length, it engages with every part of the bottle wall; and (c) cleaning solution is uniformly applied to all parts of 110 the brush between the convolutions of the material, the solution being discharged in jets which coöperate in an effective manner with the brush fiber. If desired, the cleaning solution can be forced through the jet openings under pressure; and (d) by spirally arranging the brush fiber around the spindle and spacing the convolutions of the 115 spiral, the fibers will readily be flexed laterally when the bottle is placed over the brush and removed therefrom.

It will be evident that many modifications of the brush can be made without interfering with the general structure and purpose 125 of the same, hence I wish it to be understood that my disclosures and the description herein are purely illustrative and are not intended to be in any sense limiting, as widely differing embodiments and applications of 130

the invention will suggest themselves to those skilled in the art without departing from the spirit and scope thereof.

What I claim is:

- 5 1. A brush comprising a hollow spindle, a spiral row of fiber material fixed thereto and arranged to form a relatively large number of convolutions of uniform length, said spindle being formed with a spiral row of jet openings extending midway between adjacent convolutions of the fiber material and 20 a jet opening at its free end, and a ring of fiber material extending laterally from the free end of said spindle and surrounding the opening therein.
- 10 2. A brush comprising a hollow spindle, a spiral row of fiber material fixed thereto and arranged to form a relatively large number of convolutions of uniform length, said spindle being formed with a spiral row of jet openings extending midway between adjacent convolutions of the fiber material and a ring of fiber material extending laterally from the free end of said spindle.
- 15 2. A brush comprising a hollow spindle, a spiral row of fiber material fixed thereto and arranged to form a relatively large number of convolutions of uniform length, said spindle being formed with a spiral row of jet openings extending midway between adjacent convolutions of the fiber material and 25 a jet opening at its free end, and a ring of fiber material extending laterally from the free end of said spindle and surrounding the opening therein.

In testimony whereof I have hereunto signed my name.

JOHN C. MILLER.
